UNITED STATES PATENT OFFICE.

JAMES ARKELL, OF CANAJOHARIE, NEW YORK.

DESIGN FOR GLOBES.

Specification forming part of Design No. **11,429**, dated September 23, 1879; application filed August 2, 1879.
[Term of patent 7 years.]

To all whom it may concern:

Be it known that I, JAMES ARKELL, of Canajoharie, in the county of Montgomery and State of New York, have invented a novel Design for Globes, of which the following is a full, clear, and exact description, reference being had to the accompanying photographic illustration, making part of this specification.

A represents the globe proper, B the meridian-ring, C the equatorial dial, and D the pedestal or support of what is known in the market and to those skilled in the art as a "terrestrial globe."

I design the apparatus with its polar shaft or spindle *a* protruding at each end, and projecting some distance beyond the ring B, and with the ends of said shaft *a* formed to represent an arrow, as shown, the point of which, *b*, protrudes from the north pole, (to which the point of the magnetic needle always points,) the arrow's point thus always indicating that the pole of the globe adjacent to said arrow-point is the north pole.

Of course the size and shape of the protruding ends of the polar shaft *a* may be varied, and the details of the design may be changed without losing its character as sought to be patented, the characteristic feature consisting in the projecting polar shaft with an arrow-head spear-point, or other similar shape, to indicate by the pointed end of the shaft which is the north pole of the globe.

What I claim, and desire to secure by Letters Patent, as a new design in globes, is—

A globe-fixture having its polar shaft protruded at both ends, and made to present an arrow-like appearance, as shown in the accompanying illustration.

Witness my hand and seal this 30th day of July, 1879.

JAS. ARKELL. [L. S.]
